EDGE SETTER

Stevenson A. Dobyne, St. Louis, Mo., assignor to
 Champion Shoe Machinery Company, St. Louis,
 Mo., a corporation of Missouri

Application September 21, 1931, Serial No. 563,911

3 Claims. (Cl. 12—77)

This invention relates generally to a device for setting sole edges, and particularly to such a device which is adapted for use with the usual finishing machine of a shoe repair shop.

In the use of setters in shoe repair shops it is recognized that the setting tool itself is to be operated but a relatively short period of time since the setting operation upon sole edges requires but relatively little time as compared to some other operations, and as a general rule in a shoe repair shop the same workman performs each of the various operations on shoes undergoing repair. Accordingly it is unnecessary under such circumstances as the use of a setting tool in a repair shop that the setting tool should remain heated at all times. However, in accordance with the heating devices which have been previously employed in connection with setting tools of the type referred to, it has been necessary to maintain the tool heated during all working hours of the shop, or else substantial delays would be encountered when a workman desired to set a job, in view of the fact that the heating devices heretofore employed have been relatively slow in their action. If, however, the setting tool was maintained continuously heated, it is apparent that a great loss of energy would be present naturally increasing the expense of operating the device.

An object of this invention generally stated is to provide a heating device for a setter which is adapted to bring the setter to the desired temperature within a relatively short period of time.

A further object of this invention is to provide a friction device for heating a setting tool.

A more specific object of this invention is to provide a friction device for heating a setting tool in which the friction device will automatically adapt itself to engage the maximum area of the setting tool.

A further object of this invention is to provide a device for controlling a position of a friction heating device for a setting tool.

Other objects will become apparent to those skilled in the art when the following description is read in connection with the accompanying drawing, in which

Figure 1 is a plan view illustrating the heating device and control mechanism therefor, for a setter as employed upon the usual finishing machine of a shoe repair shop;

Figure 2 is a detail view in side elevation taken along line 2—2 of Figure 1, and illustrating particularly the control mechanism for the friction heater of this invention;

Figure 3 is a detail sectional view taken along line 3—3 of Figure 1 and illustrating particularly the friction device of the present invention;

Figure 4 is a perspective view showing the friction device of the present invention.

Generally stated in accordance with the present invention a suitable assembly of friction material is provided and adapted to be moved into engagement with a face of the usual setting tool such as is employed upon finishing machines in a shoe factory. While the setting tool is being revolved at a relatively high rate of speed the friction device may be moved into engagement therewith so that it acts in the nature of a brake, but in view of the fact that the setting tool is being rotated at a relatively high rate of speed the heat generated by the action of the friction device is sufficient to rapidly heat the setting tool to the desired temperature. In accordance with one embodiment of the present invention the friction device is universally mounted so that upon engagement of the setting tool by the friction material the latter will align itself so that the maximum area thereof engages the maximum area of the setting tool, and accordingly the heating of the setting tool is accomplished in a relatively short period of time. A suitable mechanism is preferably provided for moving the friction material into and out of engagement with the setting tool and a spring may be employed for forcing the friction material into firm contact with the setting tool.

Referring now particularly to the drawing, a bracket 1 is carried by and may form a part of the usual framework for such a machine as the finishing machine usually employed in a repair shop. Such machines as just referred to are usually provided with a longitudinal shaft such as 2 upon which may be mounted the various tools or devices which are to be driven. It is to be understood that the shaft 2 may be driven from any desired source and preferably at a relatively high speed. A suitable bearing such as 3 may be provided for receiving the shaft 2 which may be suitably supported by the bracket 1.

At one side of the bearing 3, for instance at the back thereof, a suitable bracket such as 4 may be provided and may be secured thereto by means of any suitable device, such as for instance screws 5. The bracket 4 may be provided with a cylindrical portion 6 adapted to receive a shank 7 which latter may be secured within the cylindrical portion 6 in any desired

manner. Slidably mounted upon the shank 7 is a barrel 8 having at one side thereof and extending outwardly therefrom a spindle such as 9. Mounted upon the extended end of the spindle 9 is a collar 11 rotatable relative to the barrel 8 and having a central opening 12 adapted to loosely receive the shaft 2. The central opening 12 is preferably of such size as to accommodate packing material 13 for engagement directly with the shaft. It will be understood that the collar 11 is so mounted as to be slidable axially relative to the shaft 2 in accordance with the movement of the barrel 8 along the shank 7.

15 Suitably mounted upon the outer end of the shaft 2 in any desired manner is a setting tool 14 as illustrated in Figure 1. Such a setting tool as 14 may be of the usual well known construction varying in shape and size in accordance with the particular use to which it is to be put. In the embodiment illustrated the outer end of the shaft 2 is provided with a reduced portion 15 and radially extending from the reduced portion 15 is a pin 16 adapted to cooperate with a groove, such as 17, provided on the interior surface of the setting tool 14. It will be understood, however, that any connecting arrangement may be employed for securing the setting tool 14 upon the shaft 2.

20 Mounted upon the collar 11 and at the side thereof adjacent the setting tool 14 an annular frame 18 is provided. The frame 18 is preferably formed of a channel structure as clearly illustrated in Figure 3 having an annular opening defined by the inwardly extending flange 19 and having a second flange 21 extending substantially parallel to the flange 19. The frame 18 is preferably provided with a pair of ears such as 22 extending axially therefrom in a direction away from the flange 19. The frame 18 may be pivotally mounted on the collar 11 by means of suitable pins or screws such as 23 extended through openings provided in ears 22. It will be understood that frame 18 is preferably so mounted that the flange 21 is slightly spaced from the adjacent face of the collar 11. With the frame 18 thus mounted upon the collar 11 it is apparent that a variably yieldable or pivotal movement of the frame relative to the collar 25 and about an axis extending through pins 23 is possible. Between the flanges 19 and 21 of the frame 18 suitable friction material 24, such as for instance asbestos or leather, may be assembled. Such friction material may be in the form of thin discs, any number of which may be mounted so that a substantial portion thereof is exposed through opening of the frame 18, the outer limit of which is defined by the edge of flange 19. It may be pointed out that the flange 19 preferably extends only for a sufficient distance to retain the friction material 24 in assembled position within the frame and so that the face 25 of the setter which is adapted to be heated may extend therewithin 60 in order to engage the friction material 24.

65 Mounted also upon the shank 7 is a collar 26 which may be provided with a suitable set screw such as 27 adapted to engage the shank 7 to prevent relative movement of the respective parts. The collar 26 is preferably provided with a cylindrical recess such as 28 adapted to receive a pin 29. It will be understood that the pin 29 may be secured in the collar 26 such as by a suitable threaded connection. Pivottally mounted upon the pin 29 is a lever 31 which is pro-

vided with a stop lug 32 adapted to engage the bracket 4 and a second stop lug 33 the purpose of which will be pointed out hereinafter.

A link 34 is provided for connecting the lever 31 to the barrel 8, it being understood that the link 34 is preferably attached through a suitable pivotal connection at each end thereof to the respective parts, as for instance through a screw 35 mounted in the lever 31 and through a screw 36 mounted in an extended portion of the barrel 8. From an inspection of Figure 1 it will be apparent that the lug 33 is disposed in position for engagement with the edge of link 34 as the lever 31 is rotated about its pivotal pin 29 so that the lug operates as a stop for limiting the movement of the lever 31 relatively to the link 34 in one direction.

The lever 31 and the link 34 are preferably so arranged that when the parts are in the position illustrated in Figure 1, i. e., with the friction material 24 disengaged from the face 25 of the setting tool 14, the screw 35 connecting link 34 and the lever 31 will be disposed slightly below a line drawn through pin 36 and pin 29 as is clearly illustrated in Figure 2. At the same time lug 32 is in engagement with the cylindrical portion of bracket 4 so that further clockwise movement of the lever 31 is prevented. Interposed between the collar 26 and the barrel 8 on shank 7 a suitable spring, such as for instance 37, may be provided. It is apparent that the tendency of spring 37 is to force the barrel in a direction away from the collar 26 and accordingly when the parts are in position illustrated by the full lines in Figure 2 the force of the spring will tend to cause the screw 35 to move downwardly but such movement thereof is prevented by the lug 32. When in this position it is apparent therefore that the spring 37 operates to prevent the parts from being displaced, or to prevent counter-clockwise movement of the lever 31 which would effect a movement toward the left of barrel 8. Once, however, the lever 31 has been displaced to such an extent that the pin 35 comes above the center line referred to, it is apparent that the spring 37 will operate to bias the parts in such a direction that the barrel will be moved toward the left.

From the foregoing description it is believed that the operation of the present invention will be apparent, it being understood that the friction material 24 is mounted for pivotal movement in one plane relative to the collar 12, and the collar 12 is similarly mounted for movement relative to the barrel 8 and about the spindle 9. With such an arrangement of parts it is apparent that the frame 18 containing the friction material 24 is capable of universal movement relative to the shaft 2 and the setting tool 14. Accordingly when the lever 31 is moved into position illustrated by the dotted lines in Figure 2 the spring 37 will exert a force tending to urge the friction material 24 into engagement with the face 25 of the setting tool, and at the same time the friction material 24 will align itself by virtue of its universal movement so that the maximum engageable friction area thereof is in contact with the face 25 of the setting tool 14.

It is apparent that the device hereinbefore described is susceptible of many modifications which will present themselves to those skilled in the art without departing from the spirit of the invention. It is to be understood that the invention is not limited to the specific details which have heretofore been set forth and illus-

trated in the accompanying drawing, and that the use of such features and sub-combination of features, as does not depart from the spirit of this invention, is contemplated by and within 5 the scope of the appended claims.

Having thus described the invention what is claimed is:

1. A device of the kind described comprising, a setter iron having a face adapted to be heated, 10 a friction device engageable with said face, and a universal mounting for said friction device.
2. A device of the kind described comprising, a setter iron having a face adapted to be heated, a frame having an opening substantially con- 15 forming to said face, friction material mounted

in said frame and exposed through said opening and means for moving said frame axially into position for engagement of said face with said friction material.

3. A device of the kind described, comprising, 80 a setter iron having a face adapted to be heated, a frame having an opening substantially conforming to said face, friction material mounted in said frame and exposed through said opening, means for moving said frame axially into position 85 for engagement of said face with said friction material and means for causing said material to uniformly engage said face when in said position.
